(57) CLAIM

The ornamental design for a bra decoration, as shown and described.

DESCRIPTION

FIG. 1 is a front, left and top perspective view of a bra decoration, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view showing the detail portion taken from FIG. 1.

The broken lines shown in the drawings illustrate portions of the bra decoration that form no part of the claimed design. The dot-dash broken lines depict the boundaries of the enlarged figure views that form no part of the claimed design.

1 Claim, 9 Drawing Sheets
